UNITED STATES PATENT OFFICE.

WILLIAM A. AINSWORTH, OF GRAND RAPIDS, MICHIGAN.

METHOD OF DYEING YARN AND THE LIKE.

1,299,811.

Specification of Letters Patent.

Patented Apr. 8, 1919.

Original application filed July 16, 1917, Serial No. 180,805. Divided and this application filed May 10, 1918.
Serial No. 233,647.

To all whom it may concern:

Be it known that I, WILLIAM A. AINSWORTH, a citizen of the United States of America, residing at Grand Rapids, in the 5 county of Kent and State of Michigan, have invented certain new and useful Improvements in Methods of Dyeing Yarn and the like; and I do hereby declare the following to be a full, clear, and exact description of 10 the invention, such as will enable others skilled in the art to which it appertains to make and use the same.

This invention relates to a method of dyeing yarns or similar materials such as are 15 used in the manufacture of knitted fabrics.

It is desirable at times that yarn, thread, or other like material of fibrous nature used in the manufacture of knitted fabrics may be dyed, stained, or colored either in intermittent or continuous lengths, and particularly 20 in intermittent lengths, whereby the fabric produced from said yarn has a variegated appearance; and it is a primary object and purpose of my invention to secure this coloring, dyeing or staining through a simple and 25 expeditious method of dyeing without the considerable handling, waste and shrinkage of the material which has occurred with methods of dyeing heretofore used for the 30 production of said variegated yarns or the like.

For an understanding of the invention and one way in which the method may be carried out, reference may be had to the accompanying drawing, in which,

Figure 1 is a side elevation, partly in section, showing essential parts of a machine by means of which my method may be accomplished.

Fig. 2 is a fragmentary perspective view, with parts broken away and shown in section, of the dye holder and wicks therein.

Fig. 3 is a fragmentary perspective view of a detail of structure of the machine relating to means for periodically depressing the yarn or the like.

Fig. 4 is an end elevation of the depressing cam, and

Fig. 5 is a front view thereof.

Like reference characters refer to like parts in the different views of the drawing.

The present application is a division of my previous application for patent, Ser. No. 180,805, filed July 16, 1917, now Patent No. 55 1,274,972, for winding and dyeing machine,

and only so much of the machine is shown as is necessary to disclose the method. The yarn or other similar fibrous material 1 is passed from a cone 2, or other holder on which it is wound, to another cone 3, the 60 same being carried by a vertical spindle 4 which may be driven in any suitable manner, as by a pulley 5 attached to the spindle around which a belt 6 may pass. The yarn or other material 1, preferably, passes over 65 a pin 7 and through a guiding eye 8 fastened to a block or nut 9, which is threaded on a screw-threaded spindle 10 the same being adapted to be driven by any suitable mechanism, thereby guiding the yarn or like 70 material up and down the length of the cone 3. The mechanism for driving the spindles 4 and 10 is of no importance in the present invention and the way that the spindle and shaft 10 automatically reverse at predetermined intervals is not shown or described, it being no essential part of the present invention. 75

A tank or container 11 is mounted horizontally above a suitable support 12 at a 80 point between the cones 2 and 3, and contains a quantity of liquid dye, stain, or similar coloring matter. A shaft 14 extends lengthwise of and within the container 11 on which, at spaced apart intervals, disks 15 85 are fixed, around which cylindrical rings or wicks 16 of absorbent material are secured. The container is slotted at a plurality of spaced apart intervals in its upper side, as indicated at 17, whereby the wick formed by 90 said ring of absorbent material 16 comes at its upper portion above the ends of its associated slot. It is understood that for each of the wicks 16 a thread of the material 1 wound on the cone 2 may pass to a cone 3, 95 the number of cones in alignment being immaterial. The shaft 14 may be continuously operated in any suitable manner, as by a pulley 18 secured to one end, around which a driving belt 19 may pass.

The yarn or like material 1 is carried through any suitable tension device 20 mounted on a bracket 21 at one side of a slot 17, and thence directly across the container 11 and through said slot 17 and under 100 a pin 22 which may be mounted on a bracket 23 fixed to the support 12, thence leading over the pin 7 previously described. Normally the yarn is carried so as to be clear of the wick 16. 105

Suitable supports 24 are secured at each end of the container 1 serving to rotatably carry a shaft 25 which parallels said container and under which the yarn or other material 1 passes. At a plurality of spaced apart intervals in the length of the shaft 25, cams 26 are fixed, one in alignment with each slot 17, the same being elongated and of the shape shown in Figs. 3, 4, and 5, and having opposed edges 26^a which on rotation of the shaft bear against the yarn or like material and press it into contact engagement with its associated wick 16. This cam of course may be variously formed, but in the present instance, with every revolution of the shaft 25, said material 1 is pressed twice into contact engagement with a wick 16 receiving coloring matter during such contacts, and being free of the wick during the momentary period when the member 26 lies substantially horizontal as shown in Fig. 3. The rotation of the shaft 25 may be accomplished through a driving pulley 27 secured at one end which may be driven by a belt 28. The belts 19 and 28 may be driven from any suitable source of power, either the same or separate devices, or in fact the same could be turned by hand if desired.

In operation the rotation of the spindle causes a winding of the thread, yarn, or like material 1 onto the cone 3, drawing and unwinding the same from the cone 2 and drawing it over the wick 16. As it passes underneath the member 26 with the shaft rotating it is depressed into contact with a wick 16 whereby dye or similar coloring material is applied until the pressure of an edge 26^a is removed, the yarn or thread being then released to move over and above the wick 16 until again depressed by the suc-

ceeding edge 26^a. This action causes the yarn or thread to be dyed, stained or colored in intermittent lengths, with other lengths of uncolored yarn or thread between that which has been dyed or colored. To stain or color the yarn or thread continuously, it is necessary merely to turn the shaft 25 to a position such that one of the edges 26^a holds the yarn or thread in depressed position and then draw said yarn or thread 1 under said edge, the shaft 25 remaining at rest.

I have described one means for carrying out the method of dyeing which constitutes my invention. Many other ways of accomplishing this method may be devised. My invention, accordingly, is not limited in any respect to any single type of machine for accomplishing the method, but comprehends any way of accomplishing the method defined in the claims irrespective of the particular mechanism used.

I claim:

1. The method of dyeing yarn or similar fibrous material which consists in passing the material in a continuous length from one point to another, and in intermittently wiping the same against coloring matter between said points as it passes, substantially as described.

2. The method of dyeing yarn or similar fibrous material which consists in providing a member saturated with coloring matter, then rapidly passing said material in a continuous length by said member and normally separated a short distance therefrom, and in intermittently pressing said material into wiping engagement with said member as it passes by the same.

In testimony whereof I affix my signature.

WILLIAM A. AINSWORTH.
